US0D1012582S

(12) United States Design Patent (10) Patent No.: US D1,012,582 S
Goldstein et al. (45) Date of Patent:  Jan. 30, 2024

(54) ART MATERIALS STORAGE RACK

(71) Applicants: Heather E. Goldstein, Raleigh, NC (US); Christopher M. Pizzichemi, New York, NY (US)

(72) Inventors: Heather E. Goldstein, Raleigh, NC (US); Christopher M. Pizzichemi, New York, NY (US)

(73) Assignee: Heather Goldstein, Raleigh, NC (US)

() Term: 15 Years

(21) Appl. No.: 29/891,398

(22) Filed: May 5, 2023

Related U.S. Application Data

(62) Division of application No. 29/734,026, filed on May 8, 2020, now Pat. No. Des. 996,098.
